ATTORNEY.

UNITED STATES PATENT OFFICE.

NILLS CROONHOLM, OF CORNWALL, NEW YORK.

EQUALIZER.

1,344,334.

Specification of Letters Patent. Patented June 22, 1920.

Application filed June 30, 1919. Serial No. 307,512.

To all whom it may concern:

Be it known that I, NILLS CROONHOLM, a citizen of the United States of America, residing at Cornwall, in the county of Orange and State of New York, have invented new and useful Improvements in Equalizers, of which the following is a specification.

This invention relates to pneumatic shock absorbers for vehicles such as automobiles, carriages or the like.

The principal object of the invention resides in the provision of a plurality of cylinders which are fixedly supported from the chassis of the car and pistons operating within said cylinders and connected with the axles, the said cylinders arranged in a pipe line which establishes an open communication between the respective cylinders so that on the compression stroke of one or more of the pistons the pressure will be distributed to the other cylinders, and through the pipe line whereby to establish maximum buoyancy and elasticity and furnish an absorbing action which will effectually take up the detrimental shock and jars.

A still further object of the invention resides in the provision of a device of this character which will be instantly responsive to absorb the shocks and jars; one which will be simple of construction and one which will be adjustable to accommodate itself to varying loads and conditions.

With the above and other objects in view which will appear as the nature of the invention is better understood, the same consist in the improved construction and novel arrangement of parts which will hereinafter be fully described and particularly pointed out in the claim.

In the accompanying drawings, has been illustrated, a single and preferred form of the invention, it being, however, understood that no limitations are necessarily made to the precise structural details therein exhibited but that changes, alterations, and modifications within the scope of the claim may be resorted to when desired.

Figure 1 is the plan view of the apparatus showing the same conventionally applied to a vehicle.

Fig. 2 is a side view thereof.

Fig. 3 is a vertical section through one of the cylinders.

Fig. 4 is a transverse section therethrough.

Fig. 5 is a vertical section of an air inlet valve and air relief valve.

The invention consists in the provision of the identical cylinders 1 which are arranged in pairs so that one pair is located at the front and the other at the rear of the vehicle.

Each cylinder is closed at its upper end by a crown 2, while at its opposite end it is open as at 5 except for the provision of a stop collar 3 which is threadedly connected to cylinder 1, as illustrated in Fig. 3. These cylinders are fixedly connected by a bracket 6 to the side bar of the chassis as also shown in Fig. 3.

Operating in each cylinder is a piston, 70 consisting preferably of a metal disk 7, whose diameter is preferably less than the internal diameter of the cylinder to afford a slight rocking motion of the cylinder relatively of the piston. The disk 7 of the piston is provided with a leather cup packing 8 having a flange which operates against the inner walls of the cylinder and around the marginal edge of the plate 9, so as to establish air tight connection between the cylinder and said piston. The piston is provided with a rod 10, which is operatively connected by clamps 11 with the underlying axle of the vehicle.

These cylinders are used in conjunction with the ordinary springs of the vehicle which are commonly interposed between the axle and chassis as shown at 12' in Fig. 2 so that under the action of the springs the pistons are held retracted or in down stroke 90 positions in the cylinders normally.

A pipe line 14, is provided as a source of communication between the respective front and rear pairs of cylinders 1 and it consists preferably of the fittings 13 at the front and rear branch pipes 14. Said branch pipes being connected to said fittings will, further be connected to nipples 12 by union nut 16. The two Y fittings 13 are connected together by a longitudinal pipe 15.

In this manner it is obvious that on the compression stroke of any one or more of the mentioned pistons air under pressure will be distributed to the other cylinders of the structure and against the pistons therein. In this manner the shocks and jars are properly cushioned and the force of the shock equalized and uniformly distributed.

In order that the structure will be made responsive to different loads and conditions of the vehicle, the pipe 15 is provided with an air inlet valve 17 and an air relief valve

18 as shown in Fig. 5, both connected to the longitudinal pipe 15 as shown in Figs. 1 and 2.

Fig. 5 shows the air inlet valve 17. It 5 consists of a T 19, the reduction nipple 20, the top 21, threadedly connected to the reduction nipple 20, and inside will be seen a ball 22, supported by a spring 23, an air 10 passage in the top is marked 24. The spring 23 should have enough strength to keep up the ball against the top with a pressure of 1 pound more or less, so that when the car is weighted the air will be admitted to the cylinders. The air relief valve 18 has 15 the same construction as a safety valve; it consists of a T 25, reducing nipple 26, which forms the bed for the plunger 28. 27 is the top with an air relief hole 30, 29 the spring which should be strong enough to give a 20 pressure of 25 pounds more or less. In this manner a flexible cushioning action can automatically be established according to requirements, so when the car is loaded up the superfluous air will escape through the 25 air relief valve.

In lieu of pipe connection such as illus-

trated herein in every well known conduit may be substituted therefor which will establish operative communication between the several cylinders of the equalizer and I, 30 therefore do not care to limit myself to the precise arrangement and construction of parts herein illustrated.

What I claim is:—

A shock absorber and equalizer for vehicles comprising cylinders suspended from the chassis adjacent each wheel, pistons arranged within the cylinders for reciprocatory movement, piston rods associating the pistons with the axles of the vehicle, said 40 cylinders adjacent the opposite ends of the vehicle being connected in pairs by Y-fittings, and a longitudinal pipe connecting the said Y-fittings, said pipe and Y-fitting establishing communication between all of 45 the cylinders, an automatic air inlet valve supported by said longitudinal pipe, and a self acting safety valve communicating with the said pipe.

In testimony whereof I have affixed my 50 signature.

NILLS CROONHOLM.
